CLAIM

The ornamental design for a scarf display frame, as shown and described.

DESCRIPTION

FIG. 1 is a top front perspective view of a scarf display frame, showing my new design;

FIG. 2 is a front elevation view thereof, with the rear elevation view being a mirror image thereof;

FIG. 3 is a right side elevation view with the left side elevation view being a mirror image thereof;

FIG. 4 is a top plan view thereof;

FIG. 5 is a bottom plan view thereof; and,

FIG. 6 is another bottom plan view thereof, shown in use. The broken lines shown in the drawings depict environmental subject matter, i.e., elastic and a scarf, that forms no part of the claimed design.
